UNITED STATES PATENT OFFICE.

WELLINGTON W. MUIR, OF BALTIMORE, MARYLAND, ASSIGNOR TO MUIR COMPANY,
INCORPORATED, OF BALTIMORE, MARYLAND, A CORPORATION OF DELAWARE.

CARBURETER.

1,078,590.

Specification of Letters Patent. Patented Nov. 11, 1913.

Application filed June 14, 1912. Serial No. 703,630.

To all whom it may concern:

Be it known that I, WELLINGTON W. MUIR, a citizen of the United States, and a resident of Baltimore, in the State of Maryland, have made certain new and useful Improvements in Carbureters, of which the following is a specification.

My invention relates to improvements in carbureters and it consists in the combinations, constructions, and arrangements herein described and claimed.

An object of my invention is to provide a carbureter in which the admission of fuel to the engine is automatically regulated so as to allow more fuel to enter the engine cylinder when the engine is working fast and to allow less when it is working slowly.

A further object of my invention is to provide special means for accomplishing the above named results, said means comprising a valve in an auxiliary air inlet which controls the supply of fuel that is admitted into the main air or carbureting passage.

A further object of my invention is to provide a comparatively simple and inexpensive device for accomplishing the purposes named.

Other objects and advantages will appear in the following specification, and the novel features of the invention will be particularly pointed out in the appended claims.

My invention in its preferred form is illustrated in the accompanying drawings forming part of this application in which—

Figure 1 is a side view of the device, Fig. 2 is an end view thereof, Fig. 3 is an enlarged section through the device, Fig. 4 is a section along the line 4—4 of Fig. 3, and Fig. 5 is a detail view showing a modified form of regulating device.

The device shown in the drawing consists of a casing 1 having therein a float chamber 2 containing a float 3. The latter is provided with an arm 4, which is pivotally mounted at 5 in an extension 6 of the float chamber, the end of the arm 4 on the other side of the pivot 5 being connected to a collar 7 on the valve rod 8 of a check valve 9 which controls the fuel inlet 10 giving a constant level of the fuel in the carbureter.

Extending through the body of the float chamber is a passage the lower end 11 of which is known as the constant air passage because its capacity during normal opera-

tion is not varied. It will be noted that this air passage has a central restricted portion at 11^a, known as the carbureting passage, the passage becoming wider above and below this point, and the enlarged upper portion 60 is known as the mixing chamber. A tube 12 is provided which communicates with the chamber 2. The end of this tube forms a valve seat or fuel nozzle 13 in the carbureting passage, and co-operating with the fuel regulating or needle valve 14. As shown the stem 14^a of the latter is provided at its upper end with an enlarged portion 14^b having a transverse slot 14^c (see Fig. 4). Disposed in the end of the portion 14^b and 70 arranged to project into the slot 14^c is an antifriction ball 15. The portion 14^b is disposed in a recess 16 and is acted upon by a spring 17, so as to tend to keep the valve 14 away from its seat 13. 75

The casing 1 is provided with an outlet passage 18 leading to the engine cylinder. As shown this passage is controlled by a butterfly valve 19 of the usual type. Between the float chamber 2 and the passage 80 18 is a secondary or auxiliary air inlet 20 opening into the mixture chamber 11^b. Preferably this is controlled by means of a suction-controlled puppet valve 21 whose seat 22 is formed in the rim of a plate 23. 85 The latter is provided with radiating arms 24, which support a central bearing 25.

A rod or shaft 26 is arranged to slide in the bearing 25 at one end and in a bearing 25^a which is integral with the casing 1 near the other end. The valve 21 is secured to the rod 26 which intersects the line of motion of the stem of the valve 14 and co-operates therewith as hereinafter described. A spiral spring 27 whose end bears on a 95 collar 28, which is slidably mounted on a shaft 26 tends to close the valve 21.

Referring now to Fig. 1, I have shown therein a shaft 29 which passes through the carbureter and upon which is secured the 100 butterfly valve 19. On the outer end of the shaft 29 is secured an arc-shaped cam member 30, which regulates the position of an arm 31, which is pivoted on a shaft 32, and which bears a roller 33 arranged to engage 105 the cam 30. The shaft 32 extends through the carbureter and bears a forked cam member 34 of the shape shown in Fig. 3. This cam member straddles the shaft or rod 26 (see Fig. 2) and bears on the slidable collar 110

28. The arm 31 is provided with a spring 39 attached to a regulating screw 40, the latter being connected by means of the universal joint 41 with a handle on the dash of the vehicle (not shown). By turning the member 40, the tension of the spring 39 may be adjusted.

Referring now again to Fig. 3, it will be seen that near the end of the shaft 26 is a collar 42. A frame 43 (see Fig. 4) is secured to this collar by means of a bolt 44. This frame bears a cross piece 45 upon which is mounted a set screw 46. A second cross piece 47 bears a set screw 48. Between the side members of the frame 43 is pivoted a cam member 49, provided with a bearing portion 49^a arranged to enter the slot 14^c of the head 14^d and to bear on the ball 15. Between the collar 42 and the upper side of the cam member 49 is a spring 50, which bears on the cam member 49 as shown in Fig. 4, a spring 51, bearing on the shaft or rod 26, both of these springs 50 and 51 having their ends disposed in a recess 52 in the cam member 49, as shown in Fig. 4.

From the foregoing description of the various parts of the device, the operation thereof may be readily understood.

When the throttle or valve 19 is open, the suction from the engine will begin to draw in air through the passage 11. The valve 14 is slightly open and the fuel will therefore be sucked up by the air and will be atomized and carried along with it into the engine cylinder. It will be observed that there is no necessity of throttling or priming the carburetor, but that the valve 14 is in position to cause an immediate commingling of the fuel and air when the engine first starts. Now when the suction becomes greater, the air will be drawn in with more force, but presently, due to the restricted passage 11, the suction will overcome the tension of the spring 27, and the pressure 45 of the air on the outside will force open the valve so as to allow the air to pass through the by-pass 20. The movement of the valve, however, will cause a movement of the frame, and owing to the inclination of the cam member with respect to the rod 14^b, the latter will be forced upwardly by the spring 17 as the cam member is moved to the right in Fig. 3, thus opening the fuel passage and permitting more fuel to enter.

Now the throttle 19 is on the shaft 29, and the latter is actuated by the arm 53, which in turn is controlled by the link 54 leading to the throttle lever (not shown).

In opening the valve, the arm 53 is shifted 60 from the full line position to the dotted line position, shown in Fig. 1. The segment 30 is likewise shifted and permits the arm 31 to take the dotted line position, shown in Fig. 1, under the influence of the spring 65 27, which pushes the collar 28 of the cam

member 34 before it, thus rotating the shaft 32 and the arm 31. The tension therefore of the spring 27 is released the farther the throttle is opened, and therefore a greater amount of air will enter through the bypass 20 and a greater amount of fuel will be permitted to flow past the valve 14, since the latter is moved outwardly as the valve 21 is moved inwardly. The collar 55 on the rod 26 prevents the valve from moving unduly by its engagement with the sliding collar 28.

The rate at which the fuel inlet valve 14 is opened is dependent upon the inclination of the cam surface 49^a. This may be regulated by the thumb screws 46 and 48, for it will be apparent that if the screw 48 is turned, the cam member 49 will be swung on its pivot in one direction, or the other according to the tightening or loosening of the screw. The whole frame 43 may be adjusted by means of the screw 46. Thus a proper portion of fuel may be admitted with a given movement of the valve 21.

I desire to call particular attention to the fact that this carburetor differs from those in which there is a by-pass for the admission of air when the engine is running fast but where no provision has been made for a corresponding increase of the fuel flow, as in the present invention, while the fuel is carried upwardly by the rush of air through the passage 11. The amount of fuel nevertheless is dependent not only upon the rush of air through the passage 11, but is dependent upon and proportional to the amount drawn in through the by-pass. The result is that at all times the amount of fuel supplied to the engine is in proportion to the amount of work the engine is doing, and this regulation of the fuel supply is maintained automatically under all conditions.

In Fig. 5, I have shown a modified form of the cam member 49. It may be that at times it is desirable to have a greater proportion of fuel admitted than at other times. In other words, instead of having an amount which is in proportion to the opening of the throttle, it may be best to have varying amounts, or a greater proportional amount 115 in one position of the throttle, than in other positions. To this end I may make the bearing surface of the cam member 49 of a curved form, as shown at 49^e in Fig. 5. Thus there will be a greater throw of the valve rod 14^b in certain positions of the cam 49 than in others.

I claim:—

1. In a carburetor, a main air passage having a restricted portion, a fuel inlet terminating near said restricted portion, a valve for said fuel inlet, a valve stem for said valve, a cam member arranged to be engaged by the end of said valve stem, means for holding the stem in operative re- 125

lation with the cam, an auxiliary air inlet opening, a valve for said air inlet opening, a rod connected with said last named valve, an outlet passage for the explosive gases, a 5 throttle in said outlet, means for operating the throttle, a spring for normally holding the valve of the auxiliary air inlet closed, and means operated by the throttle opening mechanism for decreasing the tension 10 of the spring, said cam member being carried by said rod.

2. In a carbureter, a main air passage having a restricted portion, a fuel inlet terminating near said restricted portion, a 15 valve for said fuel inlet, a valve stem for said valve, a cam member arranged to be engaged by the end of said valve stem, means for holding the stem in operative relation with the cam, an auxiliary air inlet opening, a valve for said air inlet opening, a rod connected with said last named valve, an outlet passage for the explosive gases, a throttle in said outlet, means for operating the throttle, a spring for normally 20 holding the valve of the auxiliary air inlet closed, means operated by the throttle opening mechanism for decreasing the tension of the spring, said means comprising an arc-shaped cam member secured to the throttle shaft, a rock shaft, an arm secured to said rock shaft, and arranged to bear on said arc-shaped cam member, another arm carried by said rock shaft, a slidble collar on said rod arranged to be engaged by the 25 second arm, one end of the spring for the auxiliary air inlet valve being arranged to bear on said slidble collar, said first named cam being mounted on said rod.

3. In a carbureter, a main air passage, an 40 auxiliary air passage, a fuel inlet in said main air passage, a valve for said auxiliary air passage, a valve for said fuel inlet, means connected with the valve in said auxiliary air passage for controlling the movement of the valve in said fuel inlet, a spring tending 45 to hold the valve of the auxiliary air passage closed, a throttle, means for operating said throttle, and means controlled by the throttle operating means for varying the tension of said spring.

4. In a carbureter, a main air passage, an auxiliary air passage, a fuel inlet in said main air passage, a valve for said auxiliary air passage, a valve for said fuel inlet, means 55 connected with the valve in said auxiliary air passage for controlling the movement of the valve in said fuel inlet, a spring tending to hold the valve of the auxiliary air passage closed, a throttle, means for operating said throttle, means controlled by the throttle operating means for varying the tension of said spring, said means comprising a cam member secured to the throttle shaft, an arm arranged to be engaged by 60 said cam member, a rock shaft secured to

said arm, and another arm carried by said rock shaft and engaging the spring at the end thereof remote from the valve to control its tension.

5. In a carbureter, a main air passage, an auxiliary air passage, a fuel inlet in said main air passage, a valve for said auxiliary air passage, a valve for said fuel inlet, means connected with the valve in said auxiliary air passage for controlling the movement of the valve in said fuel inlet, a spring tending to hold the valve of the auxiliary air passage closed, a throttle, means for operating said throttle, means controlled by the throttle operating means for varying the tension of said spring, said means comprising a cam member secured to the throttle shaft, an arm arranged to be engaged by said cam member, a rock shaft secured to said arm, an arm carried by said rock shaft, and a slidble member arranged to be engaged by said arm, a guide for said member, said spring being arranged to bear on said slidble member.

6. In a carbureter, a constant air passage, an auxiliary air passage and an outlet passage into which both the other passages discharge, a throttle valve in the outlet, a fuel nozzle in the constant air passage, a valve in the auxiliary air passage, a spring tending to maintain the air valve closed, means connected to the throttle for reducing the tension of the spring at full open throttle, a fuel valve, operating means therefor, and means connecting said operating means directly to the air valve so that the fuel valve is controlled by the suction.

7. In a carbureter, a constant and an auxiliary air passage and an outlet passage into which both said passages discharge, a 105 throttle valve in the outlet, a fuel nozzle in the constant air passage, a valve in the auxiliary air passage opening inward, a spring tending to maintain the air valve closed, an abutment for the spring and means connected to the throttle for moving the abutment and reducing the tension of the spring at full open throttle, and positive means also connected to the throttle and engaging the abutment to limit the throw of the valve.

8. In a carbureter a constant air passage, an auxiliary air passage and an outlet passage into which both the other passages discharge, a throttle valve in the outlet, a fuel nozzle in the constant air passage, a valve in the auxiliary air passage, a spring tending to maintain the air valve closed, means connected to the throttle for reducing the tension of the spring at open throttle, and means also connected with the throttle for positively limiting the flow of the auxiliary air valve, said means being controlled by the throttle to increase the possible opening of the air valve as the throttle valve is opened, a fuel valve, operating means there- 130

for, and means connecting the said operating means directly to the air valve so that the fuel valve is controlled by the suction.

9. In a carbureter, the combination with 5 a normally automatically closed fluid pressure actuated air inlet valve having a stem projecting from the valve housing, a valve controlling the supply of fuel to said housing and having a stem projecting from the 10 latter, of a cam-member on the air-inlet valve-stem engaging the stem of the fuel supply valve for transmitting opening movement of the former to the latter, and means on said air valve stem for adjusting the position of said cam member for varying the 15 throw of the fuel supply valve.

10. In a carbureter, a housing having a primary air-inlet passage, a fuel supply nozzle projecting into the same, a valve controlling the discharge end of said nozzle and having a stem projecting from the carbureter housing, an auxiliary air inlet port for said housing, a normally automatically closed fluid pressure actuated valve 20 controlling said port and having a stem projecting from said housing, a cam-member on the stem of said last-named valve engaging

the stem of the first-named valve for transmitting opening movement of the former to the latter, and means on the auxiliary air- 30 valve stem for adjusting said cam to vary the throw of the fuel supply valve.

11. In a constant level carbureter, a carbureting passage having a constantly open air inlet, a fuel nozzle in said carbureting passage, and a needle valve for said fuel nozzle, a mixing chamber into which said carbureting passage discharges, a secondary air passage opening into said mixing chamber and a suction controlled puppet valve 35 for said secondary air passage, the stems of said puppet valve and said needle valve moving in intersecting lines, two co-operating members consisting of a cam and a follower, one being connected to the secondary air 40 valve stem and the other carried by the needle valve stem whereby the needle valve is operated proportionately to the opening of the secondary air valve.

WELLINGTON W. MUIR.
